WEIGHTING MEMBER FOR CARD SORTING RACKS

Albert L. Mohrman, Brooklyn, N. Y.

Application October 14, 1949, Serial No. 121,256

3 Claims. (Cl. 211—10)

1

This invention relates to improvements in racks for holding information cards such as are utilized in business offices.

The principal object of the invention is the provision of means whereby the loss of cards from such racks due to wind or other causes is prevented.

Another object of the invention is so to construct said means as to make it applicable to racks already in use in business offices without the necessity of alterations in the racks themselves.

Still another object of the invention is so to construct said means as to provide for moving the card retaining portion thereof to an out of the way position when the same is not in use.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a card holding rack of the type to which the invention is to be applied.

Fig. 2 is a front elevation of the rack of Fig. 1 with the invention applied thereto.

Fig. 3 is a plan view of the rack shown in Fig. 2.

Fig. 4 is an enlarged vertical sectional view of the top portion of Fig. 2.

Fig. 5 is a fragmentary perspective view of the means of the invention with some parts left out to clarify the view.

Fig. 6 is a detail in perspective of the card retainer of the invention.

Fig. 7 is a detail in side elevation of the card retainer of Fig. 6.

Fig. 8 is a fragmentary sectional view illustrating the position in which the card retainer is placed when not in use.

A card rack of the type to which the invention is to be applied is illustrated in Fig. 1 and a case having a back board 10 to which are secured side boards 11 and a floor board 12, the space between said side boards being divided up into several compartments by partitions 13 which are secured to the back board 10 and the floor board 12.

According to the invention there is provided a large sheet metal plate 14 (Fig. 5) bent over at its top to form a channel 15 adapted to fit over the top of the back board 10 (Figs. 4 and 8),

2 and having a series of slits 16 to receive the partitions 13.

Plate 14 is also provided with a series of slots 17 (Figs. 2 and 3) interspersed with slits 16, the 5 slots however extending upwardly past the apex of the curved portion of the plate 14 (Figs. 4 and 8). In each of the slots 17 there is loosely mounted a card retaining device comprising a nail-like bar 18 (Figs. 6 and 7) having one end 10 flattened in the horizontal direction only to form a head 20 and having also an annular collar or shoulder 21 spaced a short distance along the bar from the head 20. At its other end bar 18 has fastened thereto as by a screw 22, a downwardly 15 extending member 23 to which is secured a flat weight or card retainer 24.

The construction is such that the shank of each bar 18 between head 20 and collar 21 resides in slot 17 and is maintained in said slot 20 for up and down sliding movements as cards are placed in or removed from the compartment with which it is associated by said head and collar.

In order to provide room in which head 20 can 25 slide up and down between plate 14 and back board 10, plate 14 is provided with several spacer blocks 25 (Figs. 4 and 5) which bear against back board 10.

In order that the weights 24 can be moved to an out of the way position when not in use, plate 14 is made of a vertical length sufficient for the lower end thereof to bear on floor board 12, the upper end of channel 15 then being spaced a short distance above the top of back board 10 (Figs. 4 and 8) to provide room for head 20. As mentioned above each slot 17 is continued a short distance past the apex of the curve in the upper portion of plate 14 and the card retainer can, therefore, be moved upward and the plate 24 35 swung past a vertical position above back board 10 (Figs. 1 and 8), the device being maintained in this out of the way position by the bar 18 40 engaging the end of slot 17.

It will be seen that the reason for flattening head 20 of bar 18 only in the horizontal direction is to permit of said head being moved about the arcuate upper end of channel 15.

While I have illustrated and described the preferred embodiment of my invention, it is to be understood that I do not limit myself to the precise construction herein disclosed and the right 50 is reserved to all changes and modifications coming within the scope of the invention as defined in the appended claims.

Having thus described my invention, what I

claim as new, and desire to secure by United States Letters Patent is:

1. A weighting member for use with a rack having a backboard and a plurality of forwardly extended partitions dividing the interior of the rack into compartments open at their fronts and tops for receiving stacks of paper comprising a flat plate, said plate having a plurality of equally spaced slits extended upward from the bottom edge thereof and having between each pair of slits a vertically extended slot, said plate having its top portion bent rearward and downward, forwardly extended horizontal bars having their rear ends slidably retained in said slots for vertical movement relative to said plate, and weights mounted on the front ends of said bars.

2. A weighting member for use with a rack having a backboard and a plurality of forwardly extended partitions dividing the interior of the rack into compartments open at their fronts and tops for receiving stacks of paper comprising a flat plate, said plate having a plurality of equally spaced slits extended upward from the bottom edge thereof and having between each pair of slits a vertically extended slot, said plate having its top portion bent rearward and downward, a plurality of weights detachably mounted to said plate, each of said weights being adapted to be slidably displaced in one of said slots in a direction relative to said plate.

3. A weighting member for use with a rack hav-

ing a backboard and a plurality of forwardly extended partitions dividing the interior of the rack into compartments open at their fronts and tops for receiving stacks of paper comprising a flat plate having a plurality of spaced slits extended upward from the bottom edge thereof and having a vertically extended slot positioned between each slit, a plurality of weights detachably mounted to said plate, each of said weights being adapted to be slidably displaced in one of said slots in a vertical direction relative to said plate, and a top member attached to said plate, said top member extending rearward and downward and adapted to retain said weights at the topmost position of their vertical displacement.

ALBERT L. MOHRMANN.
